UNITED STATES PATENT OFFICE.

MORLEY PUNSHON REYNOLDS, OF CLEVELAND, OHIO, ASSIGNOR TO W. S. TYLER COMPANY, OF CLEVELAND, OHIO, A CORPORATION OF OHIO.

REFRIGERATOR-CAR.

1,153,705.

Specification of Letters Patent. Patented Sept. 14, 1915.

Application filed August 24, 1914. Serial No. 858,203.

To all whom it may concern:

Be it known that I, MORLEY PUNSHON REYNOLDS, a citizen of the United States, and a resident of Cleveland, in the county 5 of Cuyahoga and State of Ohio, have invented a new and useful Improvement in Refrigerator-Cars; and I do hereby declare the following to be a full, clear, and exact description thereof.

10 My invention relates to ice chambers or bunkers for use with refrigerator cars and particularly to bunkers which can be folded when not in use in order to permit the entire space in the car to be utilized.

15 The object of my invention is to provide a cheap, simple and efficient form of ice bunker which can be quickly and conveniently installed in refrigerator cars and which, when not being used for containing 20 ice, can be readily folded in order that the space ordinarily occupied by the same when in use can be utilized for other packing goods.

My invention consists, generally stated, 25 in the novel arrangement, construction and combination of parts as hereinafter more specifically set forth and described and particularly pointed out in the claims.

To enable others skilled in the art to 30 which my invention appertains to construct, use and manipulate my improved ice bunker I will describe the same more fully, referring to the accompanying drawings, in which:—

35 Figure 1 is a front view of my improved bunker in position in an ordinary car, with car in section, with the left hand side showing the same with the bulkhead removed. Fig. 2 is a longitudinal sectional view of 40 one end of the car showing the bunker in position for use. Fig. 3 is a similar view with the bunker collapsed. Figs. 4 and 5 are sectional plan views taken, on the lines 4—4 and 5—5, respectively on Fig. 1.

45 Like symbols of reference herein indicate like parts in each of the figures of the drawings.

As illustrated in the drawings, my improved ice bunker 1 is installed in the ends 50 of the car A, which is provided with the floor a, the roof b, end wall c, and side walls d. The bunker 1 extends across the end of the car A and is formed of the ice chamber 2 having the movable partition or bulk-

head 3 in part of the same. The ice chamber 3 is inclosed by the stationary air space 4 on the end wall C of the car A which is formed by the frame 5 covered by the woven wire fabric 5', and by the movable air spaces 6 which are formed along each of 60 the side walls d by the frames 7 and covered by the woven wire fabric 8. The movable bulkhead 3 and air spaces 4 and 6 form the walls of the chamber 2 and such bulk-head is adapted to rest upon the floor a of 65 the car A, while above the bulkhead and connected to the car roof b is the stationary bulk-head portion 9 having the woven wire fabric 10 on the inner and outer faces of the same. The bulkhead 3 has the frame 3' 70 and lower portion of such bulk-head has its outer face formed of the woven wire fabric 11. Above such fabric 11 on the bulk-head 3 is the wooden outer face or lining 12, and in the rear of said lining is the inner face 75 13 of woven wire fabric. A lever 14 is pivoted in front of and centrally of the lower portion of the bulkhead 3, as at 14', and its lower end 14'' is adapted to engage with the floor a of the car when such lever is 80 raised in order to raise such bulk-head as hereinafter described.

Within the ice chamber 2 are the ice bars 15 for holding the ice when placed in such chamber, and such bars are supported at 85 their front or outer ends by the angle bar 16 on the bulk-head 3. The ice bars 15 are connected together in any suitable manner so as to form spaces 15^a between the same for the passage of water from the ice in 90 the chamber as melted to the drip pan 17 seated below said bars and in the car floor a, and such bars are arranged in sections across the ice chamber 3, so as to be sustained by the ice stands 18, one of which 95 supports each of said sections at the rear end of the same adjacent to the car end wall c and rests at the lower end upon the said pan. The ice stands 18 have a flange portion 18' extending up from the bar supporting portion 18'' thereon for fitting against the rear of the intermediate bars 15', while pivotally connected at 16'' to the sides of said stands and to the ends 16' on the outer or side bars 15'', which project 105 beyond the intermediate bars are the brace rods 16^a. The ice stands 18 rest within the drip pan 17 and are loosely and verti-

cally supported at their lower ends in the brackets 18^a secured on the car end wall *c*.

The movable side walls 6 of the ice chamber 2 rest at their lower ends upon the side 5 ice bars 15" and their upper ends are hinged to the side walls *d* of the car A by means of the hinges 8' on top of said walls which have the slide plates 7' connected to the same and forming part of said hinges. 10 These plates 7' extend down from the hinges 8' along the side walls *d* of the car A and slide in their guides 8" secured to said side wall.

Within the bulk-head 3 is the door opening 19 which has a door (not shown) 15 hinged and adapted to be locked therein in any suitable manner and extending up from said door and within such bulk-head is the locking bar or rod 20, which passes through 20 the top of said bulk-head and through the frame 9' of the stationary bulk-head 9. A lever 21 is pivoted at 21' to the end of an angle portion 20' on the bar or rod 20 which extends through an opening 21" in the 25 bulk-head frame 3' and within a slot 20" in the frame 19' of said door opening where said bar is adapted to be seated by such portion to hold said rod in its raised or locking position, as hereinafter described.

30 Extending horizontally through the ice chamber 3 is the movable center brace 22 which has an eye 23 projecting out from the front end of the same for fitting over the upper end of the hinge pin 23' in an 35 opening or seat 22' in the bulk-head 9, and such brace extends through the end wall 4 of the ice chamber 3 and is held in position by the locking device or catch 24 on the car end wall *c*.

40 Within openings *d'* in each of the side walls *d* of the car A are the tracks 25 which extend along the ice chamber 3, and such tracks are provided with the depressions 25' at the front and rear ends of the same, with 45 the raised portions 25" between the same. These tracks 25 are at the upper and lower ends of the bulk-head 3 and rollers or wheels 26 mounted on said bulk-head are adapted to travel on said tracks, while at the ends of 50 said tracks and beyond the depressions 25' are the upwardly projecting portions 25^a to assist in holding the rollers 26 on the tracks when the bulk-head is in either its folded or opened position.

55 The operation of my improved bunker 1 is as follows:—When the parts are assembled in position to form the ice chamber 3 as shown in Fig. 1, and it is desired to fold up or collapse the same, the door in the 60 opening 19 is opened and the operator enters the ice chamber 2, and any ice remaining in said chamber can be cleaned out of the same through said door. The lever 21 is pulled out into the door space from its seat 20" in 65 the door frame 19' sufficiently to allow the

angle portion 20' on the bar 20 to drop down to the bottom of the opening 21" in said frame, which will drop the said bar down within the movable bulk-head 3 and free its upper end from its opening or seat in the 70

frame 9' of the bulk-head 9, and this operation can be accomplished any time after the door is opened in order to move the bulk-head 3, as hereinafter described. The center brace 22 is now unlatched or unlocked at its 75 rear end by the catch 24 and is swung forward at its front end by the engagement of the eye 23 with the pivot pin 23', so that

such brace can then be seated or confined in the opening 22' in the bulk-head 9, and the operator then lifts or raises each of the 80 movable sides 6, so that their lower ends are freed from the ice bars 15, by means of the slides 7' on said sides moving in the guides

8" on the car side walls *d*, and then such 85 sides are swung to the car roof *b* on their hinges 8' on the ends of said slides. With

the sides 6 thus in position under the car roof *b*, the operator can then swing out the center brace 22 on its pivot pin 23' from 90 within its seat 22' in the bulk-head 9 to its position formerly occupied in the ice chamber 2, so that it will be under said sides and then it can be held at its rear end by the

catch 24, which will thus hold said sides 95 under said roof. The ice bars 15 are then raised in each of their sections, to an angle sufficient to allow the back brace rods 19

pivotaly connected to the end bars 15" and to the ice stands 18, to swing forward, which 100 will cause such stands to go back against the end *c* of the car A and away from engagement with the ice bars to thereby free such bars from said stands and thus allow the

said bars to drop down into the ice pan 17 105 on the bottom *a* of the car. The movable bulk-head 3 being now free to be moved to the rear or end *c* of the car A, all that is required is to raise the lever 14 on the same,

so that the end 14" on the lever engaging 110 with the floor *a* of the car A will lift said bulk-head, when upon forcing said bulk-head backward while it is being raised, the rollers 26 on the same will travel in the

tracks 25 and from within the front depressions 25' therein onto the raised portions 25" in said tracks. Upon the further pushing back of the bulk-head 3 along the tracks 115 25, the rollers 26 on said bulk-head will drop into the depressions 25' at the rear of

said tracks, thereby lowering said bulk-head and sustaining the same at the rear of the car A and adjacent to the end wall *c* of said car. To again form the ice chamber 2

the movable bulk-head 3 is lifted so that its 120 rollers 26 are moved out of the rear depressions 25' in the tracks 25 by again raising the lever 14, so that it engages the floor *a* of the car A, and upon then drawing such bulk-head forward while so raised it will

125

bulk-head forward while so raised it will 130

135

bulk-head forward while so raised it will 140

145

bulk-head forward while so raised it will 150

155

travel along said tracks to its forward or open position with its rollers 26 in the front depressions 25' in said tracks where such bulkhead can be held by raising the locking bar 20. The ice bars 15 are again raised and positioned on the ice stands 18, then the center brace 22 is unlocked and swung back into the bulk-head 9, so that the side walls 6 can then be lowered on their hinges 8, 10 along the sides *d* of the car A, to allow their lower ends to rest upon the outer ice bars 15'', after which said brace is swung from the said bulk-head under the roof *b* of the car and locked at its rear end. The door in 15 the opening 19 in the bulk-head 3 can now be closed and locked and the ice chamber 2 so formed is ready for the ice to be placed therein and on to the bars 15 and 15', so that it will be obvious when the bunker 1 is 20 in use, the solid face on the bulk-head 3 will allow the circulation of the air into the car body by the iced air passing from the ice chamber down through said bars and out through the screen 11 at the bottom of said 25 bulk-head and back into said chamber through the screens 10 on the stationary bulk-head 9.

Various modifications and changes in the design, construction and operation of my 30 improved bunker may be resorted to without departing from the spirit of the invention or sacrificing any of its advantages.

It will thus be seen that in the use of my improved bunker, the proper circulation of 35 the iced or cooled air will be had into the body of the car from the bunker and from the body into the bunker.

My improved bunker can be easily and quickly assembled in position or collapsed 40 at the ends of the car by easy and convenient operations, and when folded or collapsed it will occupy little or no space in the car end and will not be in the way of using the space in the car occupied by the 45 bunker when in its open position. The bunker can be easily and quickly handled by an unskilled person for setting into position or folding, and will not be liable to get out of working order at any time or from 50 any cause.

What I claim as my invention and desire to secure by Letters Patent is:—

1. A refrigerator car having a movable transverse partition, an ice grate formed of 55 a series of bars and supported at its front end on said partition, and movable means at the rear of said bars for supporting the same in a horizontal position and for permitting the same to drop down to a horizontal position at the bottom of the car.

2. A refrigerator car having a movable transverse partition, an ice grate formed of 60 a series of bars and supported at its front end on said partition, and movable stands 65 at the rear of said bars for supporting the

same in a horizontal position and for permitting the same to drop down to a horizontal position at the bottom of the car.

3. A refrigerator car having a movable transverse partition, an ice grate formed of 70 a series of bars and supported at its front end on said partition, movable stands at the rear of said bars for supporting the same in a horizontal position, and means connected to said bars and stands for permitting the bar to be raised and be dropped 75 down to a horizontal position at the bottom of said car.

4. A refrigerator car having a movable transverse partition, an ice grate formed of a 80 series of bars and supported at its front end on said partition, movable stands at the rear of said bars for supporting the same in a horizontal position, and brace rods for supporting the same in a horizontal position, 85 and brace rods pivotally connected to said bars and stands for permitting said bars to be raised and be dropped down to a horizontal position at the bottom of the car.

5. A refrigerator car having a movable 90 transverse partition, an ice grate composed of a plurality of independent sections, each formed of a series of bars and supported at its front end on said partition, movable stands at the rear of each of said sections 95 for supporting the same in a horizontal position, and means connected to said bars and stands for permitting the sections to be raised and be dropped down to a horizontal position at the bottom of said car.

6. A refrigerator car having a movable transverse partition, an ice grate composed of a plurality of independent sections, each formed of a series of bars and supported at 100 its front end on said partition, movable stands at the rear of each of said sections for supporting the same in a horizontal position, and brace rods pivotally connected to said bars and stands for permitting said sections to be raised and be dropped down to a horizontal 105 position at the bottom of the car.

7. A refrigerator car having an ice bunker formed with a front wall having a fixed portion and a removable portion, and movable members for forming the side walls of said 110 bunker and adapted to be raised and supported under the car roof from the fixed portion of said wall.

8. A refrigerator car having an ice bunker formed with a front wall having a fixed 115 portion and a removable portion, and members forming the side walls of said bunker and hinged at their upper ends for being adapted to be raised and supported under the car roof from the fixed portion of said 120 wall.

9. A refrigerator car having an ice bunker formed with a front wall having a fixed portion and a removable portion, an ice grate 130 formed from a series of bars in the bottom

of said bunker, and members forming the side walls of said bunker and hinged at their upper ends, said members being adapted to be raised from said ice bars and 5 swung on said hinges for being supported under the car roof from the fixed portion of said wall.

10. A refrigerator car having a movable transverse partition for forming the front 10 wall of an ice bunker, an ice grate formed of a series of bars in the bottom of said bunker, members forming the side walls of said bunker and hinged at their upper ends for being adapted to be swung and supported 15 under the car roof, and sliding means connected to said members for permitting the same to be raised from said ice bars.

11. A refrigerator car having a movable transverse partition for forming the front 20 wall of an ice bunker, movable members for forming the side walls of said bunker and adapted to be raised under the car roof, and swinging means for supporting said members under said roof.

25 12. A refrigerator car having a movable transverse partition for forming the front wall of an ice bunker, movable members for forming the side walls of said bunker and adapted to be raised under the car roof, and 30 a brace pivotally mounted under the car roof for supporting said members under said roof.

35 13. A refrigerator car having a movable transverse partition for forming the front wall of an ice bunker, movable members for forming the side walls of said bunker and adapted to be raised under the car roof, a stationary bulk-head above said movable partition, and extending down from said 40 roof, and a brace pivotally mounted on said bulkhead for supporting said members under said roof.

45 14. A refrigerator car having a movable transverse partition for forming the front wall of an ice bunker, movable members for forming the side walls of said ice bunker and adapted to be raised under the car roof, a stationary bulk-head above said movable partition and extending down from said 50 roof, said bulk-head having a space within the same, and a brace pivotally mounted on said bulk-head for supporting said members under said roof and adapted to be seated in said space to raise said members.

55 15. A refrigerator car having a movable transverse partition for forming the front wall of an ice bunker, movable members for forming the side walls of said bunker and adapted to be raised under the car roof, 60 means for supporting said members under said roof, and means for locking said means in its supporting position.

16. A refrigerator car having a movable

transverse partition for forming the front 65 wall of an ice bunker, movable members for forming the side walls of said bunker and adapted to be raised under the car roof, a brace pivotally mounted under the car roof for supporting said members under said roof, and means for locking said brace in its 70 supporting position.

17. A refrigerator car having a movable transverse partition for forming the front 75 wall of an ice bunker, movable members for forming the side walls of said bunker and adapted to be raised under the car roof, a stationary bulk-head above said movable partition and extending down from said roof, a brace pivotally mounted on said bulkhead for supporting said members under said roof, and means for locking said brace in its supporting position.

18. A refrigerator car having a movable transverse partition for forming the front 80 wall of an ice bunker, movable members for forming the side walls of said ice bunker and adapted to be raised under the car roof, a stationary bulk-head above said movable partition and extending down from said roof, said bulk-head having a space within 85 the same, a brace pivotally mounted on said bulk-head for supporting said members under said roof and adapted to be seated in said space to raise said members and means for locking said brace in its supporting position.

19. A refrigerator car having a collapsible ice chamber provided with movable walls for forming the same, and a movable bottom for said chamber normally disposed above 100 the floor level of the car and adapted to be lowered to the floor of the car when collapsed.

20. A refrigerator car having an ice chamber, an ice supporting bottom for said chamber removably supported at its front end, and movable means at the rear of said bottom for supporting the same in horizontal position above the bottom of the car and permitting the same to drop to a horizontal position at the bottom of the car.

21. A refrigerator car having an ice chamber, an ice supporting bottom for said chamber removably supported at its front end, and movable stands at the rear of said bottom for supporting the same in horizontal position above the bottom of the car and permitting the same to drop down to a horizontal position at the bottom of the car.

In testimony whereof, I, the said MORLEY 120 PUNSHON REYNOLDS, have hereunto set my hand.

MORLEY PUNSHON REYNOLDS.
